UNITED STATES PATENT OFFICE.

FRED M. CARROLL, OF YONKERS, NEW YORK, ASSIGNOR TO THE TABULATING MACHINE COMPANY, OF ENDICOTT, NEW YORK, A CORPORATION OF NEW JERSEY.

RECORD-FEEDING MACHINE.

Original application filed December 2, 1922, Serial No. 604,563. Divided and this application filed December 10, 1926. Serial No. 153,802.

The invention relates to record feeding devices and more particularly to record feeding devices which are particularly adapted for use in connection with machines of the automatic type such as the combined sorter and tabulator described in my copending application No. 604,563, filed December 2, 1922, of which the present application is a division.

10 The parent case embodies an illustration of the feeding mechanism applied to a combined tabulator and sorter for feeding perforated record cards to the analyzing mechanism. It is not limited to such a use but may be employed wherever it is desired to feed records or blanks automatically to a machine. The feeding device differs from those heretofore in use in that a card magazine or pocket is provided with movable side walls in the shape 15 of endless moving belts which press against the ends of the records being fed so that they move with the belts. The pressure of the belts against the ends of the records should be adjusted so that it will be sufficient to move the 20 cards with the belt but not sufficient to cause buckling of the cards and to this end one of the belt supporting structures is resiliently mounted so that it exerts a yielding pressure against the card ends. The moving belts 25 move the records successively into cooperating relationship with a picker by means of which they may be fed one at a time to the analyzing or operating mechanism of the machine with 30 which the feeding device is associated.

35 The principal object of the invention is to provide a record feeding mechanism involving new and improved construction and arrangement of parts.

40 A more specific object is to provide a sure and accurate record feeding mechanism adapted for high speed operation.

45 Another object of the invention is to provide a record pocket or a magazine comprising movable walls for assisting in feeding the records.

50 Another object of the invention is to provide a record magazine or pocket comprising movable walls to feed the records into cooperative relationship with a card picker.

55 Another object of the invention is to provide a record magazine or pocket having movable walls at least one of which is resiliently

supported to permit proper tension between the records and the moving walls.

These and other objects, which will be 55 become apparent hereinafter, will be understood from the following detailed description which should be read in connection with the accompanying drawings in which:

Fig. 1 shows a side elevation of a record 60 feeding device according to the invention;

Fig. 2 shows a detail section of the device in Fig. 1;

Fig. 3 shows a bottom plan view of the device shown in Fig. 1 and 65

Fig. 4 shows a detail of the right hand movable wall in Fig. 1, certain parts being omitted to clearly disclose the wall supporting structure.

Referring to Fig. 1, the device is shown in 70 combination with a record carrying drum 3 provided with a card clip 27. As each card is fed from the pocket 70 it is gripped by the clip 27 and held onto the rotating drum. The upper card 29^a is shown in the act of being 75 gripped by the card clip 27. The rotating drum 3 and the card clip 27 are described in detail in the parent application referred to above and they will not be further described in the present application. It will be understood that this drum and card clip have been 80 chosen merely for the purpose of illustration as it is obvious that many other types of gripping means could be substituted for it if so desired.

85 The cards are fed to the card drum from a supply pocket 70. The side walls of this pocket are shown as comprising endless belts 71 mounted on horizontal rollers 72. One of the rollers of each wall may be provided with 90 a pinion 73, interconnected by a pair of idlers 74. One of the roller shafts also carries at its lower end a worm wheel 75 meshing with a worm 76. Said worm is driven through a shaft 77, a worm wheel 78, a worm 79 and a 95 gear 80 which through suitable gearing including bevel gears 21 and 22 is driven from a power shaft 23. The walls engaging the edges of the cards may thus be kept in constant motion to feed and hold the cards 100 against the front plate 81. A spring-expanding telescoping back plate 82, adapted to engage the walls of the pocket and to be carried thereby, may be placed against the back of

the cards. The walls may also be adapted to move slightly toward and away from each other and may be urged toward each other so as to maintain pressure against the edge of the cards. For this purpose the rollers of one of the walls may be carried in a frame 83 (see Fig. 4). The two ends of said frame may be fixed to a plate 84. Lever members 85 pivotally mounted on posts 86 may in 10 turn be pivotally connected to the frame members as at 87 and to each other as shown at 88. Said levers are pressed outwardly by a spring 89 engaging a projection 90 on one of the levers and relatively fixed wall 91. It 15 will be seen from this construction that the wall of the pocket will be resiliently forced against the cards. It should be understood, of course, that the movement of the wall and rollers is very slight and does not interfere 20 with the proper enmeshment of the several interconnecting gears which serve to drive the rollers and belt. Also the frame of the machine, as may be seen in Fig. 4, may be provided with an opening to accommodate the 25 shaft on which lower roller 72 is mounted, said opening being slightly larger than the shaft to permit of slight sidewise movement of it.

With this type of feeding pocket it is possible to remove the backing member 82 to add cards to the stack from time to time without interrupting the operation of the machine.

At the top of the card stack is a claw-like lever 92 pivoted to a reciprocating bracket 94. Also pivoted to the bracket is a link 93 attached to one arm of a bell crank 95, the other arm of which carries a roller engaging a cam 96 on the shaft 80. A spring 97 pulls 30 the bell crank and consequently also the lever 92 to the right, and the cam moves them to the left. The lever 92 is pitched slightly forward and is pulled against the card 29 by a spring 98. Thus the lever will slide over the card when moving to the right, but will jam against it on its forward stroke. This will start the feeding of the front card. In the meantime a feeding pawl 99 actuated by a bell crank 100 cooperating with a cam 101 35 will move back and forth against the face of the card alternately with the reciprocations of the lever 92, a spring 102 being adapted to hold the pawl against the card. Thus, when the card moves forward, the pawl 99 40 moving rearwardly will slip off the rear edge of the card and on the next forward stroke push the card into position to be gripped between the clips 27 and the drum 3 as shown in Fig. 1.

60 The advantages of the present type of feed mechanism are believed to be obvious but it may be stated that the device provides for a positive feed of the successive records to the picker mechanism and also permits the supply of cards in the magazine or pocket to

be replenished while the mechanism is in operation, as the back plate 82 may be removed and the pressure between the moving belts and the record cards will hold the cards in place and cause them to be fed just as if the back plate were in place. Furthermore, the device is not limited to the use of cards as paper or other flexible sheets may be fed by it, although unless the records possess a certain stiffness the back plate 82 must be in place during the feeding operation to properly hold the records.

The invention has now been described in connection with a specific embodiment for the sake of explaining and illustrating a practical and preferred form of it but it will be understood that many modifications will readily occur to those skilled in the art and I intend to be limited only as by the scope of the following claims:

What is claimed is:

1. In a sheet feeding device, a supply container having a wall compressible against a stack of sheets, and means for moving said wall for advancing the sheets.

2. In a sheet feeding device, a container, means for feeding sheets from said container, and a movable endless belt associated with said container and adapted to engage sheets within the container and urge the same toward said feeding means.

3. In a card feeding device, a container, means for feeding cards from said container, a movable back adapted to urge cards toward said feeding means, and means for continuing to so urge the cards when said back is removed.

4. In a sheet feeding device, a container, means associated with said container adapted to frictionally engage a sheet to advance the same, a picker adapted to further advance the sheet and a clip adapted to grip and carry the sheet.

5. In a sheet feeding device, a container, means associated with said container adapted to frictionally engage the surface of a sheet to advance the same, means for thereafter engaging the rear edge of the sheet and further advance the same, and grippers adapted to thereafter grip the forward edge of the sheet to carry the same.

6. In a perforated record card controlled apparatus, card feeding means, card storage means, means for delivering cards therefrom to said feeding means comprising a removable pusher member, and means for continuing the delivery of said cards on removal of said pusher member during the replenishment of said storage means with additional cards.

7. In a sheet feeding device, a supply container having side walls consisting of a pair of endless belts adapted to frictionally engage opposite edges of sheets in the container and means for continuously driving said belts

to advance the sheets through the frictional engagement of the belts with their edges.

8. In a sheet feeding device, a supply container having side walls consisting of a pair of endless belts adapted to frictionally engage opposite edges of sheets in the container and means for continuously driving said belts to advance the sheets through the frictional en-

gagement of the belts with their edges and a movable supporting structure for one of said belts with means for yieldingly urging it toward the other belt to insure frictional engagement with the edges of the sheets. 10

In testimony whereof I hereto affix my signature.

FRED M. CARROLL.
